UNITED STATES PATENT OFFICE.

ASHTON H. PRATT, OF ABINGTON, MASSACHUSETTS.

LACING-LOOP.

SPECIFICATION forming part of Letters Patent No. 372,704, dated November 8, 1887.

Application filed September 5, 1887. Serial No. 248,839. (No model.)

To all whom it may concern:

Be it known that I, ASHTON H. PRATT, of Abington, county of Plymouth, and State of Massachusetts, have invented an Improvement 5 in Lacing-Loops, of which the following description, in connection with the accompanying drawings, is a specification, like letters on the drawings representing like parts.

This invention has for its object to construct 10 a lacing-loop for boots and shoes whereby the lacing-cord may be easily passed therethrough and drawn taut.

In accordance with this invention the loop or eye is preferably made of wire bent into 15 a loop-like form and attached to the plate, and as a fastening the plate has prongs formed integral with it, which are bent upward at right angles with relation to the plate and adapted to be forced through the material from the in- 20 side out, so that the anchor-plate rests against the inside or under side of the material, while the loop or eye passes outwardly through a slit cut in the material, the loop showing at the face or front side thereof.

25 Figure 1 is a plan view of a lacing-loop embodying this invention; Fig. 2, a side elevation of the lacing-loop shown in Fig. 1; and Fig. 3, a cross-section of the lacing-loop shown in Fig. 1, taken in connection with a piece of material through which the prongs are forced and clinched.

The anchor-plate *a*, of any usual or suitable size and shape, has attached to it a loop or eye, *b*, preferably made of wire, said loop being 35 preferably elongated or made oblong, as shown, to project beyond the edge of the anchor-plate, and so, also, that the said loops or eyes may be made to project slightly beyond the edge of the material—as, for instance, a

shoe to which the said anchor-plate is attached—thus enabling a person (a shoe-lacing having been passed through the said loops or eyes) to, by a pull on the lacing, draw the opposite sides of the shoe together, as described. The anchor-plate *a* is in this instance provided with upwardly - extended prongs *c*, adapted to be forced through the material from the inside outward, after which they are turned over or clinched upon the outside of the material, the anchor-plate resting against 50 the under side thereof, while the loop or eye *b* passes up through a slit cut in the material and projects from the outside, as shown in Fig. 3.

By placing the anchor-plate *a* against the 55 under side of the material, as described, a very firm hold is given to the loop, so that it may resist a great strain.

My improved fastening is especially adapted for use upon a shoe such as shown in my application Serial No. 194,950, it having two 60 slits in the top, one at each side of the shoe and in front of the ankle.

I claim—

The lacing-loop herein described, composed 65 of the anchor-plate *a*, prongs *c*, said plate being adapted to rest against the under side of the material, and a loop or eye, *b*, which passes through the material, substantially as described.

In testimony whereof I have signed my name to this specification in the presence of two subscribing witnesses.

ASHTON H. PRATT.
